(57) **CLAIM**

The ornamental design for a pedestal mount for an electronic device, as shown and described.

DESCRIPTION

FIG. 1 is a front, top, left perspective view of a pedestal mount for an electronic device according to a first embodiment of our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is top plan view thereof;

FIG. 7 is a bottom plan view thereof;

FIG. 8 is a front, top, right perspective view of a pedestal mount for an electronic device according to a second embodiment of our new design;

FIG. 9 is a front elevational view of the pedestal mount shown in FIG. 8;

FIG. 10 is a rear elevational view of the pedestal mount shown in FIG. 8;

FIG. 11 is a left side elevational view of the pedestal mount shown in FIG. 8;

FIG. 12 is a right side elevational view of the pedestal mount shown in FIG. 8;

FIG. 13 is top plan view of the pedestal mount shown in FIG. 8; and,

FIG. 14 is a bottom plan view of the pedestal mount shown in FIG. 8.

The broken lines shown in the figures illustrate portions of the pedestal mount that form no part of the claimed design.
